Related U.S. Application Data

(62) Division of application No. 29/581,385, filed on Oct. 18, 2016, now Pat. No. Des. 841,281.

(57) **CLAIM**

(51) **LOC (12) Cl.** **02-06**

The ornamental design for a glove, as shown and described.

(52) **U.S. Cl.**

USPC **D2/619**

DESCRIPTION

(58) **Field of Classification Search**

FIG. 1 is a front perspective view of a glove, according to the present design.

USPC D2/610, 611, 616, 617, 619, 621, 623

FIG. 2 is a front view thereof; and,

CPC A63B 71/141; A41D 19/01523

FIG. 3 is a cross-sectional view thereof, taken along the line 3-3 in FIG. 2 showing the holes appearing on the front side of the glove.

See application file for complete search history.

FIGS. 1-3 shows a right hand glove. The left hand glove, which is not depicted in the drawings, is the mirror image of FIGS. 1-3.

(56) **References Cited**

The circles shown on the pads on the front side of the glove represent holes that extend through the outer layer of the pads.

U.S. PATENT DOCUMENTS

Broken lines are used to illustrate portions of the glove that form no part of the claimed design.
